(57) **CLAIM**

The ornamental design for a trunk lift assessment device, as shown and described.

DESCRIPTION

FIG. 1 is a perspective view of a trunk lift assessment device that is shown in an example environment including a base and stabilizer bar;

FIG. 2 is a rear view of the trunk lift assessment device of FIG. 1;

FIG. 3 is a front view of the trunk lift assessment device of FIG. 1;

FIG. 4 is a first side view of the trunk lift assessment device of FIG. 1;

FIG. 5 is a second side view of the trunk lift assessment device of FIG. 1;

FIG. 6 is a top view of the trunk lift assessment device of FIG. 1; and,

FIG. 7 is a bottom view of the trunk lift assessment device of FIG. 1.

The broken lines illustrate portions of the article that form no part of the claimed design.
